UNITED STATES PATENT OFFICE.

ROBERT W. INNES, OF OMAHA, NEBRASKA.

BOILER.

SPECIFICATION forming part of Letters Patent No. 598,374, dated February 1, 1898.

Application filed June 11, 1897. Serial No. 640,307. (No model.)

To all whom it may concern:

Be it known that I, ROBERT W. INNES, of Omaha, in the county of Douglas and State of Nebraska, have invented a new and Improved Boiler, of which the following is a full, clear, and exact description.

This invention is a steam-boiler having a water-jacket and a fire-box with which steam-pipes communicate, such pipes also communicating with the boiler whereby to establish a circulation through such parts and accelerate the production of steam.

This specification is the disclosure of one form of my invention, while the claims define the actual scope of the conception.

Reference is to be had to the accompanying drawings, forming a part of this specification, in which similar characters of reference indicate corresponding parts in all the figures.

Figure 1 is a longitudinal section of the invention. Fig. 2 is a sectional plan on the line 2 2 of Fig. 1. Fig. 3 is a sectional elevation looking in the direction of the arrow *a* from the line 3 3 of Fig. 1. Fig. 4 is a sectional elevation looking in the direction of the arrow *b* from the line 3 3 of Fig. 1, and Fig. 5 is a front elevation of the apparatus.

The boiler 6 is seated in suitable masonry and has a steam-dome 7. The fire-tubes of the boiler 6 open into a smoke-box 8, from which a stack 9 leads. The fire-box or furnace has a stationary grate 10, with a movable section 11 at the front thereof. The section 11 rocks on the horizontal shaft 12, one end of which is projected beyond the furnace and formed with a crank 13, by which the movable section 11 of the grate may be operated to dump the ashes into the ash-pit beneath. A removable pin 14 is employed to hold the section 11 of the grate horizontal. Upon the removal of this pin the weight of the coals on the section 11 will cause the section 11 to dump. The top and sides of the fire-box or furnace are formed of a water-jacket 15. The top of said water-jacket is braced by two water-legs 16, respectively at the front and rear of the fire-box. The water-legs 16 respectively stand on and communicate with water-beams 17, arranged, respectively, at the front and rear of the furnace. A feed-pipe 18 enters the water-jacket 15, which is therefore the primary receptacle of the water

for the furnace. Running from the rear edges of the jacket 15, from the rear water-beam 17, and from the rear water-leg 16 are 55 a series of water-tubes 19. The water-tubes 19 run rearward beneath the boiler 6, turn up at the rear end thereof, pass through the top 20 of the shell that covers the boiler 6, and communicate with a header 21. Each pipe 60 19 has an extension 30 run rearward through the masonry at the rear of the boiler and provided with a plug by which the extensions 30 are closed. The pipes 19 may be blown out by opening these extensions 30. The 65 header 21 is U-shaped, with its arms projecting forward, and from the center of the header 21 a pipe 22 leads to the top of the steam-dome 7. The pipes 19, that pass from the rear water-beam 17, extend slightly upward 70 from said beam, as illustrated in Figs. 1 and 4, so as to place the said pipes 19 in the immediate path of the products of combustion as the same pass rearward beneath the boiler 6 and thence forward through the fire-tubes 75 of said boiler. Passing from the lower rear portion of the boiler 6 are return-tubes 23, extending downward to the surface on which the boiler is built and then turning forward, running to and communicating with the rear 80 water-beam 17. These tubes 23 are therefore arranged with the greater portions of their length out of the immediate path of the products of combustion of the furnace. The water flows from the water-jacket 15 through 85 the tubes 19 to the water-line in the boiler and then returns by means of the tubes 23.

To make tortuous the passage of the gases beneath the furnace 6, I provide transverse baffle-walls 24, extending across between the 90 sides of the masonry supporting the boiler and each having a break 25 therein, said breaks being arranged at alternate sides of the walls 24, so that the gases will be made to travel tortuously beneath the boiler. The unbroken portions of the walls 24 extend upward to the lower surface of the boiler. The upper edges of the walls 24 are provided with alternately-projecting bricks, as shown in Fig. 3, to absorb the heat from the passing gases. 95 The tubes 19 run through the walls 24.

A water-column 26 is in communication with the boiler 6 by means of the pipe 27 and with the water-jacket 15 by means of the pipe

28. The water-column 26 serves to indicate the condition of the water within the boiler.

The front and rear ends of the water-jacket 15 have openings closed by plugs 29, which are 5 removable to expose the openings. Through these openings the water-jacket and the tubes attached thereto may be blown out or cleansed.

Having thus described my invention, I 10 claim as new and desire to secure by Letters Patent—

1. A boiler having a boiler proper, a shell inclosing the same, a furnace located at the forward end of the boiler and having a water-jacket at the top and sides thereof, a grate 15 within the furnace, a water-beam running along the rear edge of the grate and communicating with the water-jacket, tubes running from the rear edge of the water-jacket from the 20 rear water-beam and from the rear water-leg, the tubes passing beneath the boiler proper and running up past the rear end thereof, a header above the boiler proper with which header the said tubes communicate, a tube

leading from the header to the dome of the 25 boiler proper, and a return-tube running from the boiler proper to the furnace.

2. A boiler having a boiler proper, a shell inclosing the boiler proper, a furnace, the top and sides of which are formed by a water-jacket, a grate beneath the water-jacket, water-beams running transversely at the front and rear of the grate and between the sides of the water-jacket, a water-leg standing on each water-beam and joining the top of the 35 water-jacket, tubes running from the rear water-beam from the water-jacket and from the rear water-leg, the tubes passing beneath the boiler proper and up along the rear end thereof to a point beyond the shell, a header 40 with which the tubes communicate, a tube leading from the header to the boiler proper, and a return-tube running from the boiler proper to the furnace.

ROBERT W. INNES.
